CLAIM

The ornamental design for an edible beverage can-holder, as shown and described.

DESCRIPTION

FIG. 1 is a perspective view of an edible beverage can-holder showing our new design;

FIG. 2 is a top plan view of the edible beverage can-holder of FIG. 1;

FIG. 3 is a side elevational view of a long side of the edible beverage can-holder of FIG. 1, the opposite side being a mirror-image thereof;

(Continued)

FIG. 4 is a bottom plan view of the edible beverage can-holder of FIG. 1; and,
 FIG. 5 is a side elevational view of a short side of the edible beverage can-holder of FIG. 1, the opposite side being a mirror-image thereof.

1 Claim, 3 Drawing Sheets
